UNITED STATES PATENT OFFICE.

MARK A. DEFIBAUGH, OF SYRACUSE, NEW YORK, ASSIGNOR TO SYRACUSE WASHING MACHINE CORPORATION, OF SYRACUSE, NEW YORK, A CORPORATION OF DELAWARE.

MECHANICAL CLOTHES WASHER.

Application filed April 2, 1926. Serial No. 99,272.

This invention relates to a mechanical clothes washer of the vertical reciprocating vacuum-cup type in which inverted cups or clothes engaging members are mounted on a vertically movable carrier in uniformly spaced relation circumferentially about the axis of a vertically movable plunger to which the carrier is secured.

This plunger is usually power driven through a suitable gland in the bottom of the clothes-containing tub or vat preferably through the medium of a motor-driven lever and therefore has a definite stroke or distance of travel which is transmitted to the cup carrier when the machine is in operation but owing to the more or less irregularity in arrangement and quantity of clothes to be operated upon within the tub or vat it becomes necessary to provide resilient connection between the cups and carrier or between the carrier and plunger to allow limited movements of those parts relatively to the positively driven plunger in order to compensate for the irregularities and varying thicknesses of the clothes throughout the area of the tub to prevent overload upon or stoppage of the motor and also to relieve the various parts of the washing mechanism and gland from excessive strains.

The means most commonly employed to allow for this compensating movement is to provide compression spring connections between the cups and rigid arms of the carrier and to house the compression springs in telescoping parts on the cups and carrier respectively so that the telescoping parts may serve as guides for the vertical movement of the cups relatively to their supporting arms on the carrier which, of course, necessitates more or less close fitting of the telescoping parts and also requires the use of stops for limiting the extension of those parts.

Heretofore, so far as I am aware, the entire carrier including the telescoping members for supporting and guiding the cups in their relative vertical movements have been made of cast metal or aluminum alloy which has necessarily been of relatively large size and weight to withstand the strains to which they are subjected.

It has been found, however, that the cups and their supporting arms of the carrier are subjected to widely varying strains in practically all directions due to the irregularities

of the surface and varying thicknesses of the clothes operated upon which, after a greater or less period of use, results in excessive wear of the telescoping parts and in some instances causes the breakage of those parts and cup-supporting arms of the carrier which requires replacement of the entire carrier particularly when cast as a single unit.

The main object of the present invention is to provide a lighter, stronger, more durable and more efficient cup carrier than has heretofore been practiced, by rigidly securing the cups directly to the outer ends of a corresponding number of spring arms having their inner ends secured to a hub on the plunger and thereby to preserve the resiliency of the arms throughout their entire lengths so that the cups may be free to move in all directions under pressure upon the clothes without overstraining any of the parts at the same time causing the cups to be restored to their normal positions when relieved from pressure.

Another object is to curve the spring arms in such a manner as to increase their resiliency in all directions and thereby to further relieve the strains upon the hub of the carrier and its supporting plunger.

Another object is to avoid relative movement between the cups and carrier arms and thereby to obviate the objectionable pounding noise, excessive wear and unsanitary joints incidental to the use of the relatively movable parts.

Another object is to reduce the wear between the plunger and gland through which it is movable and thereby to reduce the liability of leakage through the gland.

A further object is to construct the cups in such a manner as to reduce the liability of crushing or bending the same when subjected to pressure against the clothes. In other words the objects as specifically enumerated are as follows:

To avoid wearing and cutting of the clothes; to reduce the tendency to wrap around the center post or gland; to eliminate the most frequent, expensive and annoying service problems; to prevent overloading the motor and at the same time to enable the cups and carrier to withstand a greater pressure than has heretofore been practiced; to render the entire washer mechanism more sanitary; to reduce foundry troubles inci-

dental to casting and also to reduce the number of parts and machine operations and incidentally to cut down the cost of manufacture.

Other objects and uses will be brought out 5 in the following description:

In the drawings;

Figure 1— is a top plan of a mechanical washer embodying various features of my invention.

10 Figure 2— is a vertical sectional view of the same on line 2—2— Figure 1—.

As illustrated this clothes washer comprises a cup carrier 1— consisting in this instance of a head or hub 2— spring arms 3— removably secured at one end to the head 2—, and cups 4— secured at their apexes to the outer ends of the arms 3—.

15 The head or hub 2— is provided with a central vertical opening 5— for receiving a vertically removable plunger 6— as shown by dotted lines in Figure 2— said hub being provided near its top with a diametrical opening for receiving a locking pin or key 7— which is adapted to be inserted 20 in one or the other of a plurality of openings at different levels in the plunger 6— for holding the carrier in different positions along the plunger according to the amount of clothes in the tub to be operated upon.

25 Any suitable means (not shown) may be employed for reciprocating the plunger 6— vertically through a stroke of definite length for affecting a corresponding movement of the cups into and out of engagement with the clothes in a manner somewhat similar to that shown in the patent to J. N. Durschug 35 1,480,157 January 8, 1924.

30 The locking pin 7— may be provided with one or more notches 8— adapted to be engaged by a spring 7— for holding the pin in its locking or released positions.

35 The hub 1— is preferably made of strong metal and is provided with a plurality of in this instance three, vertical openings 9— arranged in uniformly spaced relation circumferentially about the axis of the hub 1— equal distances therefrom for receiving the inner ends of the spring arms 3—, said hub being also provided in its upper face with 40 radial grooves 10— extending laterally and outwardly from the corresponding vertical openings 9— to form seats for the adjacent horizontal portions of the spring arms to hold said arms against turning movement in their respective sockets 9—.

45 The arms 3— are all of the same form and size, each arm consisting of a solid rod of spring metal preferably curved in cross section and gradually tapered from its inner end to its outer end or from its point of attachment to hub 1— to its point of securement to the apex of its cup 4—, the extreme inner end of said arm being offset vertically, in this instance downwardly, to form a supporting stem 11— which is seated in one of

the sockets 9— and has its lower end threaded and engaged by a nut 12— for firmly holding the inner end of the arm in fixed relation to the hub 1— with the adjacent horizontal portion of the arm seated in the corresponding groove 10— for holding the arm against turning movement in the socket 9—.

50 Each of the spring arms 3— extends downwardly or laterally and outwardly from the upper end of the stem 11— in the form of a compound curve and terminates at its outer end in a vertical stem 13— which is passed through a vertical opening 14— in the apex of one of the cups 4— and has its lower end threaded and engaged by a nut 15— co-operating with a shoulder 16— on the upper end of the stem 14— for firmly clamping the cup to the arm.

55 It will be seen from the foregoing description taken in connection with the drawings that the upper portions of the arms 3— are substantially horizontal and that they are curved outwardly and circumferentially from the stems 11— and then gradually curved outwardly and downwardly to the vertical stems 13— so that while the inner ends of the horizontal portions are substantially radial to the axis of the hub 1— the remaining portions are deflected circumferentially 60 and downwardly some distance to one and the same sides of their radial portions whereby the cups 4— will be yieldingly supported on the outer ends of their respective arms wholly at one side of a radial plane passing through 65 the points of securement of said arms to the hub 1—.

70 These arms, although comparatively slender, are found to be sufficiently strong to exert the desired pressure upon the clothes and at 105 the same time to withstand a greater pressure than would be possible with relatively larger cast metal arms.

75 The cups 4— are all of substantially the same form and size and are preferably conical, 110 and circular in cross section with their lower ends normally disposed in substantially the same horizontal plane.

80 It is evident, however, that when the apexes of the cups are secured in the manner described to the outer smaller ends of the arms 3—, they will be free to yield in all directions and independently of each other when brought into pressing coaction with the more or less uneven surfaces of the clothes due to 115 the peculiar curves and resiliency of the arms 3— throughout their lengths and also to the circumferentially offset relation of the cups to the radial planes passing through the inner ends of the arms.

85 It has been found that the conical formation of the cups enables them to wholly withstand the strains to which they are subjected against crushing or buckling and that by 120 securing the outer vertical ends of the arms 125

directly to the apexes of the cups not only enables the latter to yield in all directions under different pressures against different portions of the rims thereof but also relieves 5 the connections between the arms and cups from undue strains by distributing the pressure stresses along practically the entire length of the arms.

This distributed resiliency of each arm 10 from its point of attachment to the cup to its point of attachment to the hub not only permits the cup to adjust itself to inequalities in the surface of the clothes operated upon but also permits each cup to adjust itself under 15 the same conditions independently of the other cups and greatly relieves the lateral or tilting strains upon the hub —1— and also upon the plunger —6— which incidentally reduces wear upon the guidepost for the 20 plunger and consequent leakages of the water through the gland in which the plunger is movable.

Furthermore the rigid securing of the outer ends of the spring arms —3— to the 25 apexes of the cones obviates all of the objections incidentally to the use of telescoping parts and compression springs therein commonly heretofore employed in machines of this character.

It is also obvious that if any one of the 0 cups or its supporting arm should become impaired for any reason it may be easily and quickly removed and replaced without disturbing any of the other arms or cups carried thereby.

What I claim is:

1. In a clothes-washing device, a vertically movable plunger, a hub on the plunger, spring arms having one end secured to the hub, and cups secured to the other ends of the arms, said arms having different portions thereof curved horizontally and vertically respectively to afford greater resiliency between the cup and hub.

2. In a clothes-washing device, a vertically movable plunger, a hub on the plunger, a longitudinally tapered spring arm having its larger end secured to the hub, and a cup secured to the smaller end of the arm, said

arm having different portions thereof curved 50 horizontally and vertically respectively to increase its resiliency in different directions.

3. In a clothes-washing device, a vertically movable plunger, a hub on the plunger, a plurality of horizontally and vertically curved 55 spring arms secured at one end to the hub in a uniformly spaced relation circumferentially, and cups secured to the other ends of the arms, each arm having different portions thereof curved in different planes, such planes 60 being in angular relation.

4. In a mechanical clothes washer, a vertically reciprocating hub having a plurality of sockets in uniformly spaced relation circumferentially, spring arms having their inner 65 ends inserted in corresponding sockets, each arm having different portions thereof curved in different directions and in planes approximately at right angles to each other, and cups rigidly secured to the outer ends of said arms. 70

5. In a mechanical clothes washer, a vertically reciprocating hub having a plurality of sockets in uniformly spaced relation circumferentially, spring arms having their inner 75 ends inserted in corresponding sockets, each arm having one portion curved laterally in a plane at approximately right angles to the axis of the hub and another portion curved vertically, and clothes-engaging members secured to the vertically curved portions. 80

6. In a mechanical clothes washer a vertically reciprocating hub having a plurality of sockets in uniformly spaced relation circumferentially, spring arms having their inner 85 ends inserted in corresponding sockets, each arm having a compound curve circumferentially and axially with relation to said hub, and cups secured to the outer ends of the arms.

7. A spring arm for supporting the clothes- 90 engaging member of a mechanical clothes washer, said arm having one portion curved in a substantially horizontal plane and another portion curved in a substantially vertical plane.

In witness whereof I have hereunto set my hand this 17th day of March, 1926.

MARK A. DEFIBAUGH.
